UNITED STATES PATENT OFFICE.

CHARLES DE LUKACSEVICS, OF NEW YORK, N. Y., ASSIGNOR, BY MESNE ASSIGNMENTS,
TO EDMUND LOFFLER, OF NEW YORK, N. Y.

CARBURETER.

1,248,278.

Specification of Letters Patent. Patented Nov. 27, 1917.

Application filed December 4, 1916. Serial No. 134,950.

To all whom it may concern:

Be it known that I, CHARLES DE LUKACSEVICS, a citizen of the United States, residing at New York, in the county of New York and State of New York, have invented new and useful Improvements in Carbureters, of which the following is a specification.

This invention relates to improvements in carbureters for internal combustion engines; 10 and its principal objects are to provide a simply constructed, compactly organized carbureter with easily accessible parts wherein waste of gasoline is reduced to a minimum, the amount of fuel delivered in the mixing 15 chamber is merely proportionate to the requirements of the engine under varying conditions of speed and load, the relative proportions of the constituents of the mixture are maintained throughout the whole range 20 of engine speed, and the fuel is delivered into the mixing chamber in such condition and in such manner as to insure its immediate, uniform and thorough admixture with the air.

With the above objects in view the invention consists generally in the provision of a fuel nozzle which discharges through a number of ducts or passages of small diameter whose discharge ends are in different planes 30 and whose inlet ends lead from a reservoir or chamber, preferably located above the normal fuel level and containing an absorbent agent which is constantly saturated with the liquid fuel and in the provision of a mixing or carbureting chamber in concentric relation to the fuel nozzle through 35 which the air necessary to complete the combustible mixture is induced by the suction of the engine, the arrangement being such that 40 the air passes in relation to the discharge openings of the nozzle and by suction takes up the fuel which is discharged at close and regular intervals and in finely divided state by the ducts whereby it becomes readily and 45 uniformly vaporized in admixture with the air. The invention further consists in the operative combination and the relation between the fuel nozzle having the features of structure just mentioned and a specially constructed valve for proportioning the constituents of the mixture and regulating the quantum of mixture which is passed to the engine and for proportionately regulating the velocity of the air as it passes in relation to the fuel nozzle. The invention fur-

ther consists in certain features of organization whereby the parts of the carbureter are securely held together by a single stem or post located centrally and axially of the carbureter and provided with a suitably arranged fastening nut or nuts. 60

An embodiment of the invention is illustrated in the accompanying drawings, wherein:

Figure 1 is a vertical central sectional view of a carbureter in which the features 65 of the invention are incorporated.

Fig. 2 is a horizontal sectional view on the irregular line 2—2 of Fig. 1.

Fig. 3 is a horizontal sectional view on 70 the line 3—3 of Fig. 1.

Fig. 4 is a horizontal sectional view on the line 4—4 of Fig. 1.

Fig. 5 shows in plan and side elevation 75 the upper discharge member of the fuel nozzle.

Fig. 6 is a side elevation of the lower discharge member of the fuel nozzle.

Similar characters of reference designate 80 corresponding parts throughout the several views.

The casing of the carbureter provides a chamber 1 to which fuel is delivered from a fuel nozzle 2 and air is delivered from an air supply pipe 3 which, if desired, may 85 be provided with an air heating medium (not shown) or may, for the purpose of heating the air, extend in suitable relation to the engine exhaust system (not shown). As shown, the pipe 3 opens directly into an air inlet chamber 4 having a concentric valvular partition 5 through which the air passes toward the center of the casing whence it ascends to the chamber 1 and in relation to valvular devices, to be hereafter described, for controlling 90 its volume and velocity.

As shown and preferred the nozzle 2 is arranged in upright relation centrally and axially of the carbureter casing, said nozzle being supported by a pipe or tube 6 which 100 extends transversely through the casing and leads from any suitable source of fuel supply, for example and as is preferred, a fuel chamber 7 carried by the carbureter casing and equipped with conventional float feed mechanism 8 for maintaining a constant level and a strainer 9 for preventing the passage of solid particles into the pipe or tube 6.

The volume of the mixture of the fuel 110

delivered to the engine as also the velocity of the air which passes in relation to the nozzle 2 is regulated by a valve 10. As shown the carbureter casing is formed below the chamber 1 with a portion of uniform width or diameter which provides a guide 11 for the valve 10; and said valve, which is at all times in surrounding relation to the nozzle 2, has a close sliding fit within and against its guide 11 and is movable lengthwise of said guide by suitable mechanism, conveniently a rack bar 12 secured to or formed with the valve 10 and an operating pinion 13 engaging said rack bar and mounted on a shaft 14 journaled in the side walls of an extension 15 of the guide 11, said shaft carrying an operating crank 16 at one end.

For the regulation of the velocity of the air, provision is made for a variable throat-way 17 in concentric external relation to the discharge end of the nozzle 2 and for the provision of said throatway, said nozzle or the valve 10, or both of them, as is preferred, may be specially formed. As shown the nozzle 2 has a regular flare from its lower to its upper or discharge end and the valve 10 has an inwardly projecting, annular Venturi-type rib 18. By this arrangement, as the valve is raised, the efficient area of the throatway 17 is diminished and as the valve is lowered such area is increased with resultant increase or decrease of the velocity of the air passing through the throatway.

For the regulation of the volume of the mixture delivered to the chamber 1 the valve 10 co-operates with a stationary valve element 19 supported within the chamber 1. As shown the element 19 is of cup-like form and opens directly to the motor suction tube, its cylindrical wall having openings 20 through which the combustible mixture passes inward from the chamber 1. The base 19^a of the cup-like valve element 19 provides a seat for co-operation with the upper edge of the valve 10 and the communication of the chamber 1 with the internal space defined by said valve is through the variable throatway or space normally occurring between the upper edge of the valve 10 and the seat afforded by the base 19^a. Obviously as the valve is raised the space between it and the base 19^a is diminished and as the valve is lowered such space is increased. With the decrease of the area of communication between the internal space defined by the valve 10 and the chamber 1 there is, of course, a decrease of the suction influence in such internal space but this does not interfere with the supply of fuel necessary for low speed running since the low inductive value of the suction influence is compensated by the increase in the velocity of the air which moves in a stream line formation past the discharge end of the nozzle

and which takes up the gasoline vapor or finely divided gasoline at the period when its velocity is greatest or nearly so.

The valvular partition 5 enables a permanent adjustment of the possible maximum air supply in accordance with varying conditions such as the power capacity of the engine and the density of the air in a particular locality; and said partition includes a stationary element 5^a having openings 5^b 75 and a closely surrounding adjustable element 5^c having openings 5^d. By turning the element 5^c about its axial center the openings 5^d are brought more or less into registry with the openings 5^b whereby the latter may either be partially uncovered to any desired degree or completely uncovered. For the purpose of such adjustment the element 5^c has its base provided with an axial tubular extension 5^e upon which is made 85 fast, externally of the carbureter casing, by intermeshing corrugations or otherwise, an adjusting lever 21 bearing with frictional braking pressure against a backing nut 22, said lever being pressed against said nut by 90 a helical spring 23 surrounding the extension 5^e.

To insure the correct proportioning of the mixture under varying conditions of suction the regulating valve 10 has combined therewith, and as a functional part thereof, an air control valve 24 which is movable as a unit with the valve 10 with which it is connected by supporting straps 25 and which operates below the nozzle supply tube 6 and in relation to a closely surrounding stationary annular apron 26. The valve 24 has a cup-shape with a substantially closed base 24^a; and its cylindrical wall is provided with openings 27 affording 100 communication between the chamber 1 and that part of the carbureter casing which surrounds the nozzle 2, the effective area of said openings being regulated by the apron 26 which diminishes such area as the valve 110 24 is raised and increases it as the valve 24 is lowered.

The nozzle 2 has a central bore which is in open communication with the tube 6 and which terminates at its upper end in an enlargement providing an oil well 28. The nozzle is provided with two sets of fuel discharge ducts, 30 and 31, of small diameter and which are preferably arranged radially at regular, and somewhat close intervals. 115 These ducts are arranged at suitable outward and upward inclinations and terminate in planes one above the other, the ducts 30 terminating in the lower plane and the ducts 31 terminating in the higher plane. 120 The ducts 30 function for a certain range of low speeds when the inductive value of the air is, of course, reduced, to supply the amount of fuel necessary for low speed running, without however, furnishing any 130

excess and thereby causing the mixture to be unduly rich. Both sets of ducts, 30 and 31, function for a certain range of high speeds including the maximum speed, in which the inductive value of the air is sufficiently high. In any event, the fuel is delivered from the nozzle in accordance with the inductive value of the passing air stream and, as regards condition, in radial jets at close intervals and in finely divided state, its incorporation with the air stream being thoroughly effected in consequence of its uniform vaporization, upon or almost immediately succeeding, its discharge from the nozzle.

In the preferred embodiment of the invention the ducts 30 and 31 have their inlet ends above the normal fuel level. Accordingly the upper portion of the well 28 provides a chamber for absorbent or capillary material 29, which is partly submerged in the fuel in the well and whose upper portion, projecting above the normal fuel level, is constantly saturated with the fuel.

As a matter of economy and convenience in manufacture, as also convenience in cleaning and renewing, the ducts 30 and 31 are formed as grooves in the outer faces of the members 32 and 33 which may be aptly designated as fuel discharge members and preferably have an inverted frusto-conical form whereby they may be nested, the member 33 within the member 32 and the latter within a conforming seat provided therefor at the upper end of the tubular post which constitutes the main part or body of the nozzle.

In the construction of the carbureter the base of the float feed chamber 7 and the annular wall with which the fuel supply tube 6 is formed are cast integral and the said wall is formed, above with a seat for the body part which provides the chamber 1 and the valve guide 11 and below with seats for the lower section which provides the air chamber 4 and for the valvular partition 5 and apron 26; the attachment flange 34 is cast with the stationary valve element 19 and is formed with a seat for the upper edge of the wall of the chamber 1; and the parts assembled in the relation described are held together by a stem 35 located centrally and axially of the carbureter casing and preferably threaded through a boss 36 formed with the tube 6, said stem being retained by the previously mentioned nut 22 fitted on its lower end and by a nut 37 fitted on its upper end and bearing against the upper surface of the base 19^a of the valve element 19. The fuel discharge members 32 and 33 have central openings through which the stem 35 passes and are clamped or fixed in their operative positions by nuts 28 fitted on the stem 35 below the valve element 19. Obviously by removing the nuts

37 and 38 the carbureter may be completely dismantled.

I claim as my invention:

1. In a carbureter, in combination, a casing having an air inlet, and a fuel nozzle located centrally and axially of said casing and discharging above said air inlet, said nozzle having sets of fuel discharge ducts of small diameter projecting radially and at close intervals from said well and terminating in higher and lower planes, both located above the normal fuel level, said nozzle having separably related nesting discharge members whose faces are radially grooved to provide said ducts. 80

2. In a carbureter, in combination, a casing having an air inlet, a fuel nozzle located centrally and axially of said casing and discharging above said air inlet, said nozzle having sets of fuel discharge ducts of small diameter projecting radially and at close intervals from said well and terminating in higher and lower planes, both located above the normal fuel level, said nozzle also having separably related nesting discharge members whose faces are radially grooved to provide said ducts and a fixed stem projecting through said discharge members and carrying securing nuts therefor. 95

3. In a carbureter, in combination, a casing having an air inlet at its lower end, a jet delivery fuel nozzle arranged centrally of said casing and discharging above said air inlet, a tubular regulating valve surrounding said nozzle and having a close sliding fit within said casing, a chamber located above said nozzle, the upper end of said valve being in open communication with said chamber in any open position of said valve, and a stationary valve element having an overhanging portion located above said nozzle and within said chamber, said valve being slidable axially of said casing and projecting into said chamber 110 whereby its upper end may coöperate with the over-hanging portion of said valve element to vary or close the space through which the interior of said valve may communicate with said chamber, the latter communicating through said valve element with the motor suction tube. 115

4. In a carbureter, in combination, a casing having an air inlet, a jet delivery fuel nozzle arranged centrally of said casing and discharging above said air inlet, a carbureting chamber arranged above said nozzle, a fixed stem disposed axially of the nozzle and of the casing, the latter being made in separable sections, and nuts fitted upon the opposite ends of said stem to clamp the sections of the casing in organized relation, the removal of the nuts at the upper end of the stem enabling the dismantling of the casing. 130

5. In a carbureter, in combination, a casing having an air inlet, a jet delivery fuel nozzle arranged centrally of said casing and discharging above said air inlet, a carbureting chamber above said nozzle, said nozzle having sets of fuel discharge ducts of small diameter and having separably related nesting discharge members whose faces are radially grooved to provide said ducts, a fixed stem disposed axially of the nozzle and of the casing, the latter being made in separable sections, a nut fitted upon the upper end of said stem and serving to secure the sections of the casing in clamped relation, and means surrounding said stem below said nut and engaging said discharge members to hold them in operative nested relation.
6. In a carbureter, in combination, an annular wall formed with a transverse fuel tube, a fuel nozzle secured to and upright from said tube, an attachment flange, a body part clamped by and between said annular said wall and said attachment flange, a valve within said body part and slideable axially thereof, a stationary valve element carried by said attachment flange and projecting downward therefrom into said body part, said valve coöperating at its upper
- end with said valve element, a stem secured to and said fuel tube and projecting through said nozzle and through said valve element and a nut mounted upon the upper end of the stem and engaging said valve element whereby to maintain the clamped relation of the body part between said annular wall and said attachment flange.
7. In a carbureter, in combination, a fuel nozzle having an oil well adapted as a container for absorbent material which projects above the normal fuel level and sets of fuel discharge ducts projecting radially and at close intervals from said well and supplied by said absorbent material, said ducts terminating in higher and lower planes and a carbureter casing concentric to the nozzle and having an air inlet below the nozzle whereby the air, drawn through said casing by the engine suction, flows past the discharge ends of said ducts with inductive effect.

In testimony whereof I have hereunto set my hand in presence of two subscribing witnesses.

CHARLES DE LUKACSEVICS.
